UNITED STATES PATENT OFFICE.

CHARLES E. BUELL, OF SPRINGFIELD, MASSACHUSETTS.

APPARATUS FOR CONVEYING PARCELS OR GRAIN BY ATMOSPHERIC PRESSURE.

SPECIFICATION forming part of Letters Patent No. 338,138, dated March 16, 1886.

Application filed June 1, 1885. Serial No. 167,138. (No model.)

To all whom it may concern:

Be it known that I, CHARLES E. BUELL, a citizen of the United States, residing at Springfield, in the county of Hampden and State of Massachusetts, have invented a certain new and useful Improvement in Conveying Parcels, Grain, and other Matter by Atmospheric or Gas Pressure, of which the following is a full, clear, and exact description.

10 The object of my invention is to convey parcels and materials through conducting-mains by means of air from a compressing apparatus, or by gases resulting from super-heated steam or other sources.

15 My invention consists, primarily, in a pneumatic-carrier system having an air-tight receiver provided with motor gas-inlet, and opening into an outlet transmitting main which is equipped with an outwardly-opening valve 20 to allow grain to pour from the receptacle into the main, and a receiver for the transmitted grain having a cushioning device upon which the grain is received.

25 In the accompanying drawings, Figure 1 represents my invention in partial elevation and section for carrying parcels. Fig. 2 similarly represents a detached part of same. Fig. 3 shows in partial vertical section devices for operating my invention as applied to carrying grain. Fig. 4 shows in top plan view a 30 relaying-station, and Fig. 5 shows in partial vertical section a modified form of devices shown in Fig. 3. Fig. 6 is a cross-section of a double conveyer, and Fig. 7 is a partly-sectional side elevation of my system of grain-conveying.

35 Referring to Fig. 1, A is a receptacle of any suitable character, with a man-hole or lid, L, closing air-tight thereon, and held by screw S 40 against pressure.

P is an induction-pipe from an air or gas supplying apparatus provided with valve V, for controlling the supply of pressure.

45 P' is a conducting-pipe from the said supplying apparatus.

M is a main for conveying parcels, &c.

V' is a flap-valve in the main M, hinged at u.

B' is a branch pipe from the main P', to admit pressure therefrom under control of valve 50 V' into the main M after the carrier E (shown in dotted lines) has been driven by the air-

pressure in the receptacle A beyond the branch pipe B'.

In transmitting parcels the carrier E is laid on a table, C, in the receptacle A on a level with and so as to enter main M, when pressure is let into the receptacle A, or it can be manually inserted in the main M. Pressure being maintained in P' as the carrier E passes into section M' of the conducting-main, it 60 opens valve V' and automatically operates the valve-opening mechanism D (which will form subject-matter for a future application) by making operative an electric circuit in an obvious manner; but mechanical means without 65 electricity may be used to automatically operate the valve. As the carrier E passes by valve V' said valve closes, and the air or gas rushes between the carrier E and valve V', through another branch pipe, B', also containing a valve 70 in the circuit of the valve-operating mechanism D, said valve V' acting to close the section M'. The carrier E preferably fits the main M close, and is covered with felt or leather to an extent to make it fit properly. Several sections, 75 like M', can be used, the mechanism D being intended to automatically run back and close after a predetermined time. When the carrier E enters the section P' of Fig. 2, which is in continuation of the main M, it compresses 80 the air therein and is gradually slowed up, and as it enters a receiving-case, A, it is projected against the curtain or swinging piece X and drops into the case, from which it can be removed through man-hole L'. A safety-valve, S V, is provided in the section P' to relieve a too great pressure therein. The momentum of the carrier E carries it from one section to the next, the pressure in the preceding section being relieved by escape, as 85 shown by arrows at V'.

To properly convey grain and other like material that might clog a pipe if supplied to the pipe in too rapid a manner, the grain should be fed into the pipe, so as to float in 95 the moving air passing through the pipe. In order to do this the box A, Fig. 3, is filled or partly so through man-hole L and a bucket-wheel, W, revolved by electro-mechanical or other preferred means by its buckets b, takes 100 up the grain and projects or feeds it to the main M. The pressure enters the receptacle

A through pipe P and passes into the main M, carrying the grain with it.

T is a shelf or lip on the mouth of the pressure-pipe to catch dropping grain.

5 V V' are valves in the pressure-pipe and main, respectively, for controlling the flow of pressure.

Fig. 4 shows in plan view a double receptacle, A A, so arranged and divided that one apartment can be filled while the other apartment is being emptied through the main M. Branches and valves are shown for transferring the pressure alternately to the said apartments.

15 Fig. 5 shows suction-tubes h h, used in place of wheel W of Fig. 3, to feed the grain properly to the main. The air or gases enter the receptacle A through pipe P. The receptacle A can be filled through pipe N from a remote station, then be closed by valve V⁶, and the pressure enters through pipe P to send the grain forward. A pipe (not shown) may be used instead of the man-holes L to fill the apartments A A of Fig. 4.

25 Fig. 6 shows a section of a double main, M M' of Fig. 1, fed with pressure through valvular branch pipes B', from a pressure-pipe, P, common to both, so that parcels can be sent in opposite directions simultaneously from one supply of pressure. The air and gases can be forced through water before entering the pipe P or main M, to cool, dry, or moisten the air or gases. If the water is colder than the air, it cools and dries it. If the water is hot, it moistens the air.

30 To maintain a uniform temperature in the pipe P and main M during transit, they may be protected as steam-pipes are to prevent condensation by coating or covering them with a non-conductor of heat.

40 In Fig. 7 I have shown more in detail my system of conveying grain by relays of pressure. 1 may represent an air-compressor, such as shown in my United States Letters Patent No. 246,657, the air-cylinder of which is connected with the pressure-pipe P. A is the grain-receptacle, supplied with grain through the man-hole L, or from a distance through the pipe N, and having an internal air-pressure through the branch-pipe q of the pipe P. The receptacle A opens into the pipe P under regulation of the valve F, and said pipe is conjoint with the main M. This main leads to and empties in a second receptacle, A, at another station, which receptacle is provided with a relay-compressor, 2, similar to compressor 1. This compressor 2 has the press-

ure-pipe P, in which are the valves V and F, for controlling the air and grain, respectively. Enough pressure will go into the receptacle A 60 at this station to act upon the upper surface to assist the suction in the main in withdrawing and forwarding the grain. At the terminal station is also arranged a compressor, 3, similar to those at 1 and 2 and connected to a receiver, K, by pipe R, to supply air to said receiver to form a cushion for the incoming grain, so as to prevent injurious impact. The receiver K and terminal of the main M preferably meet in a hopper, A², from which 70 the grain may be withdrawn as desired. The receptacle A of the second station is shown provided with a receiver, K', which is similar in construction to receiver K, and which may be supplied with air from compressor 2 or from 75 an independent compressor.

I do not herein claim, broadly, the independency of the sections, means for operating a signal in connection with my system, means for controlling under all circumstances the air 80 in the sections, and means for venting the sections, but will embody said features in other applications.

I do not limit my invention to the single purpose of conveying grain, as obviously its 85 usefulness is extensible to the transmission of other matter.

What I claim is—

1. In a pneumatic carrier system, the air-tight receptacle A, the motor-gas inlet, and the main M, opening from said receptacle and provided with an outwardly-opening valve to allow grain in said receptacle to pour into said main, and a receiver for the transmitted grain provided with an elastic or yielding medium 95 to receive the grain without injurious impact, substantially as described.

2. A pneumatic tube in sections, each provided with a valve or gate hung pendulous within said section, and an air-escape vent between said gate and the contiguous section, substantially as described.

3. In a pneumatic-carrier system, a double main, M M', for transmitting material in opposite directions, combined with a single supply-pipe, P, and valvular connections therewith, substantially as described.

In testimony whereof I have hereunto set my hand this 30th day of May, A. D. 1885.

CHARLES E. BUELL.
